Geo. F. Kimmel, ATTORNEY.

UNITED STATES PATENT OFFICE.

FRANK M. CRUMLEY, OF URBANA, INDIANA, ASSIGNOR, BY DIRECT AND MESNE ASSIGNMENTS, OF ONE-THIRD TO GILBERT GRANDSTAFF AND ONE-THIRD TO E. V. SHOLTY, BOTH OF URBANA, INDIANA.

WINDOW VENTILATOR.

Application filed November 27, 1926. Serial No. 151,120.

The invention relates to a ventilator and more particularly to the class of window ventilators.

The primary object of the invention is 5 the provision of a ventilator of this character, wherein the same is capable of adjustment so as to be placed within a window frame to permit the window sash to be brought in engagement therewith, whereby 10 ventilation may be had through the window, without liability of the ingress of sleet, rain, or snow to the interior of the enclosure having the window, the adjustment of the ventilator permitting the same to be adaptable 15 for various sizes of window frames.

Another object of the invention is the provision of a ventilator of this character, wherein the same can be placed within an opening constituted by the partial raising 20 of the window sash in the frame and will shield such opening to constitute a deflector for a draft of air passing through the opening from without to the interior of the building.

25 A further object of the invention is the provision of a ventilator of this character, wherein the entire structure is made from metal and is united together in the parts thereof in a novel manner, so that such parts 30 will be firm and secure and the said ventilator capable of varying adjustment to adapt the same to different sizes of the window frames.

35 A still further object of the invention is the provision of a ventilator of this character, which is extremely simple in construction, thoroughly reliable and efficient in its purpose, strong, durable, readily and easily applied to and removed from a window 40 frame and inexpensive to manufacture.

With these and other objects in view, the invention consists in the features of construction, combination and arrangement of parts, as will be hereinafter more fully described, in detail, illustrated in the accompanying drawing, showing the preferred embodiment of the invention and pointed out 45 in the claims hereunto appended.

In the accompanying drawing:

50 Figure 1 is a fragmentary vertical sectional view through a window frame and its lower sash, showing the ventilator construct-

ed in accordance with the invention applied in one position.

Figure 2 is a front elevation of the window ventilator. 55

Figure 3 is a view similar to Figure 2 looking toward the inner face of the ventilator.

Figure 4 is a fragmentary detailed sectional view taken on the line 4—4 of Figure 3 looking in the direction of the arrow. 60

Figure 5 is a detailed fragmentary sectional view taken on line 5—5 of Figure 3 looking in the direction of the arrow. 65

Figure 6 is a miniature detailed sectional view similar to Figure 1 showing the ventilator upset and reversed from the position in Figure 1. 70

Similar reference character indicates corresponding parts throughout the several views in the drawing.

Referring to the drawing in detail, A designates generally a portion of a window frame, which is of the conventional type 75 and B the lower sash, slidably mounted within the frame in the usual or customary manner between the guide strips 10 and 11, respectively, carried by each side of the window frame A between its sill 12 and the 80 head of said frame, the head being not shown.

Adapted to be removably and adjustably held within the window frame is the ventilator constituting the present invention, 85 which will be hereinafter more fully described in detail.

The ventilator comprises a pair of telescopically connected extensible sections 13 and 14, respectively, each being formed with 90 a lower bottom plate 15 and an upper or top head plate 16, both being formed from sheet metal. The outer ends of these sections 13 and 14 have the lower and upper plates 15 and 16 connected together through 95 the medium of vertically disposed folded over end strips 17, each made from sheet metal and are connected to said plates through the medium of split rivets 18. The plates 15 and 16 are spaced apart and have 100 arranged to cover such space screens or reticulated or wire mesh fabric 19, each being engaged at its inner end in a folded-over end strip 20 and at the opposite longitudinal

edges by folded-over longitudinally extending border strips 21, while the outer end edge of the fabric 19 is folded in with the outer end strip 17, connecting the plates 15 and 16 together. The strips 20 and 21 are fastened to the plates 15 and 16 through the medium of split rivets 22, while linked to the outer strip 17 of each extensible section and riveted to the fabric 19 is a reinforcing strip 23. The fabrics 19 constitute the ventilating panels of the sections 13 and 14 as will be apparent.

These fabrics 19 are fastened on their outer spaces of the sections 13 and 14 so as not to interfere with the extension of the sections when telescopically connected in relation to each other. The top plates 16 of the sections 13 and 14 are extended to provide angularly disposed awning-like shields 24 and 25, respectively, having the straight free end portions 26 disposed parallel with the plane of the sections 13 and 14 but spaced a distance therefrom and held in such spaced relation by the braces 27 connected thereto and to the sections 13 and 14, respectively.

The section 14 has its bottom plate 15 and the canopy extension 25 bent on themselves to provide the guide flanges 28 and 29, respectively, to provide runways for the edges of the extensions of the bottom plates 15 and the extensions 24 of the other section 13 and in this manner these sections 13 and 14 are slidably connected with each other as a unitary structure.

The canopy extensions 24 and 25 overhang the ventilating panels 19 of the sections 13 and 14 and the canopy extensions terminate a distance above or from the free edges of the bottom plates 15 of the sections 13 and 14 so as to form an air way as indicated by the arrows in Figures 1 and 6 of the drawing for ventilating purposes to admit air from without the enclosure to the interior thereof.

In the use of the ventilator the sections 13 and 14 are extended relative to each other so that their outer ends will engage between the guide strips 10 and 11 of the window frame A and the canopy extensions 24 and 25 will be positioned either as shown in Figure 1 or Figure 6 of the drawing. When positioned as shown in Figure 1 of the drawing the ventilator will shield sleet, rain, or snow and prevent the same from entering through the opening in the window, when the sash B is brought against the same at the top thereof. When the ventilator is upset and reversed when engaged in the window frame A as shown in Figure 6, the canopy extensions 24 and 25 deflect the currents of air upwardly from without the enclosure to the interior thereof as indicated by the arrow in said Figure 6 of the drawing.

It will be apparent that the ventilator is

capable of various adjustments and positionings relative to the window frame, so that it will accommodate itself to various sizes of window frames and to several different uses as illustrated in Figures 1 and 6 of the drawing.

From the foregoing it is thought that the construction and manner of operation of the device will be clearly understood and its application, therefore a more extended explanation has been omitted.

What is claimed is:—

1. A ventilator for the purpose set forth comprising a pair of interfitted extensible sections, each of said sections consisting of a pair of spaced, superposed plates, a screen panel extending across the space between said plates, vertically and longitudinally extending means secured to the plates for fixedly securing the panel in position, said vertically extending means connecting the plates together at the ends thereof, and an angle shaped canopy extension projecting from one of said plates and opposing and spaced from said panel.

2. A ventilator for the purpose set forth comprising a pair of interfitted extensible sections, each of said sections consisting of a pair of spaced, superposed plates, a screen panel extending across the space between said plates, vertically and longitudinally extending means secured to the plates for fixedly securing the panel in position, said vertically disposed means connecting the plates together at the ends thereof, an angle-shaped canopy extension projecting from the upper of said plates and opposing and spaced from said screen, and bracing means secured to the extension and to the lower of said plates.

3. A ventilator for the purpose set forth comprising a pair of interfitted extensible sections, each of said sections consisting of a pair of spaced superposed plates, a screen panel extending across the space between said plates, vertically and longitudinally extending means secured to the plates for fixedly securing the panel in position, said vertically disposed means connecting said plates together at the ends thereof, an angle-shaped canopy extension projecting from one of said plates and opposing and spaced from the screen, said extension including a vertical portion, and bracing means between said vertical portion and the other of said plates.

4. A ventilator for the purpose set forth comprising a pair of interfitted extensible sections, each of said sections consisting of a pair of spaced, superposed plates, a screen panel extending across the space between said plates, vertically and longitudinally extending means secured to the plates for fixedly securing the panel in position, said vertically extending means connecting the plates together at the ends thereof, an angle

shaped canopy extension projecting from one of said plates and opposing and spaced from said panel, and a reinforcing strip extending transversely of and secured to said panel in proximity thereof and further abutting against a vertically extending means for connecting the plates at one end together.

5. A ventilator for the purpose set forth comprising a pair of interfitted extensible sections, each of said sections consisting of a pair of spaced, superposed plates, a screen panel extending across the space between said plates, vertically and longitudinally extending means secured to the plates for fixedly securing the panel in position, said vertically disposed means connecting the plates together at the ends thereof, an angle shaped canopy extension projecting from the upper of said plates and opposing and spaced from said screen, bracing means secured to the extension and to the lower of said plates, and a reinforcing strip extending transversely of and secured to said panel in proximity thereof and further abutting against a vertically extending means for connecting the plates at one end together.

6. A ventilator for the purpose set forth comprising a pair of interfitted extensible sections, each of said sections consisting of a pair of spaced superposed plates, a screen panel extending across the space between said plates, vertically and longitudinally extending means secured to the plates for fixedly securing the panel in position, said

vertically disposed means connecting said plates together at the ends thereof, an angle shaped canopy extension projecting from one of said plates and opposing and spaced from the screen, said extension including a vertical portion, bracing means between said vertical portion and the other of said plates, and a reinforcing strip extending transversely of and secured to said panel in proximity thereof and further abutting against a vertically extending means for connecting the plates at one end together.

7. A ventilator for the purpose set forth comprising a pair of interfitted extensible sections, each formed throughout of metallic material and consisting of a pair of spaced, superposed plates, a screen panel extending across the opening formed between said plates, means attached to the outer faces of said plates for fixedly securing said panel in position, said means extending vertically and longitudinally with respect to the plates, the vertical portion of said means connecting the plates together at the ends thereof, a canopy extension integral with and extending forwardly from one of said plates and opposing and spaced from the screen panel, and a brace member between the outer portion of the extension and the other of said plates.

In testimony whereof, I affix my signature hereto.

FRANK M. CRUMLEY.
